UNITED STATES PATENT OFFICE

2,346,862

PILOT CIRCUIT SWITCH

Elmer Muchow, Maplewood, Mo., assignor to Automatic Control Corporation, St. Louis, Mo., a corporation of Missouri

Application November 21, 1941, Serial No. 419,861

3 Claims. (Cl. 200—146)

The present invention relates to an electric switch, and more particularly to a combination including a pilot circuit switch that may be employed in connection with a main switch so as to relieve arcing at the main switch.

The invention comprises in general a main switch of a particularly desirable construction, that may be subject to arcing, because of vibration of the contacts due to impact when the contacts are closed, and a pilot switch that is closed when this vibration of the main switch occurs, which pilot switch is not subject to arcing from the vibration, and which is sufficient to carry enough load in parallel with the main switch to avoid arcing of the main switch.

An object of the invention is to provide such a pilot switch as above described.

A broad object is to provide in combination with the main switch, subject to vibration and arcing, a pilot switch not subject to arcing because of vibration, which pilot switch is closed in sufficient time with respect to the vibration of the main switch to carry adequate load to prevent the arcing at the main switch.

Specifically, an object is to provide contacts and contact support for the pilot switch, enabling the contacts to vibrate together without breaking upon closure and to combine this pilot switch with the main switch, and means operated by operation of the main switch to actuate the pilot switch at or upon the operation of the main switch.

A further object is to provide a novel series of linkages and levers for operating the two switches, including means to provide a differential between the opening and closing values of the switches.

A further object is to provide a connector called a jumper, located so as to be readily removable to eliminate one of the two switches from the circuit or to re-insert said switch in the circuit as desired.

In the drawing:

Figure 1 is a front view of the switch;

Fig. 2 is a vertical medial section on the line 2—2 of Fig. 1;

Fig. 3 is a fragmental vertical section taken on the line 3—3 of the lower left hand part of Fig. 2;

Fig. 4 is a fragmental vertical section taken at the lower middle part of Fig. 2;

Fig. 5 is a broken horizontal section taken on the line 5—5 at the lower part of Fig. 2;

Fig. 6 is a fragmental section similar to the

lower part of Fig. 2, but with the switch in its other position; and,

Fig. 7 is a diagram of the connections in the switch mechanism.

5 The switch is mounted upon a front panel 10. A channel-shaped casing 11 has its flanges secured to the panel 10 and forms side walls 12 and 13 and a back wall 14 for the switch.

A primary lever, generally indicated at 15, is 10 pivoted on the pivot 16 to a differential lever 17, pivoted at 18 to the side walls 12 and 13. The differential lever, in turn, has an upstanding portion 19 attached by a spring hinge 20 to a correspondingly upstanding portion 21 of a 15 secondary lever generally indicated at 22.

The primary lever has, as a power-receiving end, a lower portion disposed opposite an opening 23 in the back wall 14, and also opposite a notch 24 extending upward from the end of the 20 differential lever 17. A power stud 25 is adapted to pass through the opening 23, the notch 24 and abut against the end of the primary lever. This stud is adapted to be driven by a movable diaphragm, such as is well known in the art, or by any suitable element, such as one moved in response to temperature or pressure changes. In the device shown, the member 25 moves toward the panel 10 upon increase in temperature or pressure. The stud 25 has a head 26 engageable over the edges of the notch 24, to apply force onto the differential lever when the stud moves backwardly.

The primary lever, at its upper end has a 35 notch providing lugs 28 that straddle a differential adjusting screw 29, that is adjustably threaded at 30 into the differential lever 17. The screw 29 is provided with a fixed flange 31 to receive the lugs 28 on one side and to receive an extending end 32 of the spring hinge 20 40 on the other side, which is serrated. This spring normally exerts a force toward the front panel 10 and thereby restricts fortuitous displacement of the screw. The screw extends through an opening 33 in the front panel 10 and is kerfed at its outer end to receive a screw driver for adjustments.

The secondary lever 22 at its lower end is provided with a resilient yieldable portion 36 that is bent, toward its lower end, to have a 45 horizontal portion 37, and additionally bent to have an end portion 38, to which are attached two armature members 39 and 40 fixed in spaced relationship by a connector 41.

On the portion 36 of the secondary lever is 50 supported a contact bar 42 adapted to span

two contacts 43 and 44, as will appear. The contact bar 42 is generally T-shaped as appears in Fig. 4. Its upper end is bifurcated to engage about a T-shaped element 45 secured to the secondary lever 36 and adapted to permit limited displacement in a swivelling manner of the upper end of the contact bar 42. The lower end of the contact bar is provided with a tongue 41 engaging through a slot in the portion 37 of the secondary lever which slot permits limited movement of the end of the contact bar relative to the lever portion 37, toward and from the panel 10.

Centrally of the contact bar 42 is a pin 49 passing through an opening in the portion 36 of the secondary lever, and adapted to be engaged by the end of a leaf spring 50 secured between this upper portion and the lower portion 36 of the secondary lever. These three members are riveted together as appears at 51 in Fig. 4.

The contact 43 is held to the inside of the panel 10 by a bridge member 53, as shown in Fig. 5. A terminal 54 is secured to the panel and to the bridge 53 to bring a lead to the bridge.

Similarly the contact 44 is provided with a bridge 55 and a terminal 56.

The armature member of the secondary lever disposes the armature elements 39 and 40 on opposite sides of magnetic poles 58 and 59. These magnetic poles have extensions 60 and 61 to act as a blow-out means, all as shown in Patent No. 2,250,016 issued to Claude M. Garner on July 22, 1941. A magnetic element 62 provides magnetic energy for the pole pieces, and all are secured together in a plastic block attached to the panel wall 14.

A stop member 64 limits movement of the lower end of the secondary lever toward the front panel 10. The stop is connected with a support by a terminal post, generally indicated at 65. This terminal post supports an upwardly extending leaf spring 66 of conducting material, normally urged by inherent resiliency to shift its upper end backwardly from the panel 10. It has toward its upper end a contact 67 adapted to engage with an opposite contact 68 held on a U-shaped contact member 69 (Fig. 3) formed of conducting and leaf spring material and attached at its other end to the terminal 54.

An adjustable screw 71 is threaded to be held in the secondary lever 21 and has an end adapted to engage the upper extension of the member 66.

The terminal 65 has a screw 72 outside the front panel 10 which is adapted removably to hold a jumper 73 of conducting material across the terminals 65 and 56.

This switch is adapted to be used for either alternating current or direct current and is flexible so as to be capable of application to varying load conditions.

Operation

Upon movement of the stud 25 toward the panel 10, the end of the primary lever 15 is displaced. It first pivots about the pivot 16 by which it is attached to the differential lever, until the portions 28 engage the flange 31. The distance traveled by the primary lever upon striking the flange 31 is determined by the adjustment of the screw 29.

After this contact is made, further movement of the end of the primary lever about the pivot 16 is prevented, and further pressure on the end 75

of the primary lever provides a direct lifting force upon the pivot 16 to displace the primary lever and the differential lever about the pivot 18 of the latter, toward the front panel 10. The displacement of the differential lever 17 with the primary lever displaces the hinge member 19 toward the front panel, which urges the upper end of the secondary lever 21 toward the front panel. This causes the secondary lever to pivot counterclockwise (Fig. 2) to urge the lower end of the secondary lever backwardly to bring the contact member 42 across the contacts 43 and 44. During the early part of the movement of the upper end of the secondary lever, the lower end, being retained by force of the magnetic field on the armature 40, resists displacement. This action distorts the yieldable part of the secondary lever, accumulating energy until the stored force exceeds the resistance of the magnet. Then the lower end draws away from the magnet. As the force of the magnet varies with an exponent of the distance from the magnet, that force diminishes rapidly once the displacement of the lower end begins, effecting a snap action. When the other armature 39 enters the field of the magnet, it reverses the action, and closes with a snap action.

Despite the flexibility of the construction of the main switch, there is a bouncing action of the contact member 42 against the contacts 43 and 44 with accompanying arcing. Where the switch is carrying, for instance, an inductive load, this arcing can occur in serious proportion. To avoid this, the pilot switch including the contacts 67 and 68 is provided. The screw 71 is adjustable so that the upper end of the spring 66 is released to close the contacts 67 and 68 prior to closure of the switch member 42 against the contacts 43 and 44. Owing to the resiliency in construction of both the members 66 and 69, the contacts 67 and 68 vibrate together and, therefore, do not bounce to cause arcing. This pilot switch, therefore, carries the load until the main switch is closed, since the pilot contacts 67 and 68 respectively join the terminals 56 and 65 and with the jumper in, the terminal 65 is connected to the terminal 56. The pilot switch provides an early acting arc-proof switch in parallel with the main switch and of sufficient size to carry the early load in the making of the contacts.

When the opposite condition occurs so that the screw 25 moves backwardly, the end of the primary lever 15 is permitted also to move backwardly. After traveling the amount permitted by the differential adjustments, the head 26 of the screw 25 engages the forward surface of the differential lever 24 and pulls it backwardly, causing the differential lever to pivot about the pivot 18 in a clockwise direction, and to draw with it the secondary lever 21 so that the latter pivots clockwise to open the switch. In this action, the contacts 42, 43 and 44 are broken before the contact 67 and 68 are parted. But the action of the pilot switch in both opening and closing is controlled by the snap-action mechanism.

The foregoing switch may be used with the connection described, and the jumper 73 in, for an A. C. inductive load, such as for a motor load of 1½ H. P. A. C. In such case, the pilot switch prevents arcing because of vibration of the main contacts. With the jumper out and the main switch only in circuit, the switch may be used for a non-inductive load A. C. or D. C. or for a

direct current load. With the jumper out and connections made from the terminal 54 to the terminal 65, the pilot switch may be used for relatively small A. C. loads.

What is claimed is:

1. In a switch mechanism, a casing, a switch lever movable in said casing, contact means on said switch lever, second contact means on the casing engageable by the contact means on the lever, a third contact, means resiliently supporting said third contact on the casing, a fourth contact engageable by said third contact, means resiliently supporting the fourth contact on the casing, said third and fourth contacts supporting means having similar vibration characteristics to cause said third and fourth contacts to vibrate together when brought into contact with each other, said first and second contacts being in parallel with said third and fourth contacts, means on the switch lever engaging one of said resilient contact mounting means when said switch lever is in position to open said main switch, said engaging means being adapted to release said contact supporting means in time to permit closing of said third and fourth contacts by the time said first and second contacts are closing so that any arcing of the first and second contacts upon closing will be prevented by transmission of the current through the third and fourth contacts.

2. In a switch mechanism, a main switch including a relatively rigid movable switch member and a relatively rigid contact engageable thereby, means moving the member toward said

contact in such wise as to cause bouncing, a pilot switch including a second switch member and a contact member adapted to be engaged thereby, said pilot switch members having similar vibration characteristics and thereby being constructed to be free of bouncing and connected in parallel with the main switch, and means to close the pilot switch at the time the main switch is closing and subject to bouncing.

3. In a mechanism of the kind described, a base, a main switch including a first contact relatively rigidly mounted on the base, a switch lever, and a second contact on the lever, automatic means including snap-action means to operate the lever to bring the second contact to the first, said switch lever being relatively rigid whereby bouncing may occur when the contacts engage, an auxiliary switch including third and fourth contacts, means mounting the third and fourth contacts separately on the base, means operated upon movement of the lever to close the main switch to effect closure of the third and fourth contacts, said mounting means for said third and fourth contacts including a relatively flexible member yieldable when the fourth contact is brought against the third, to avoid bouncing, said auxiliary switch being in parallel with the main switch and said means for effecting closure of the auxiliary contacts being adapted to close the auxiliary switch by the time the main switch contacts meet, whereby the auxiliary switch may carry the current of the main switch when the contacts of the latter are bouncing.
